ABSTRACT OF THE DISCLOSURE

A display carton for bottles, flasks, pots or like vessels having grooved necks, said carton being essentially constituted by a rectangular sheet of paperboard or like material, and preferably corrugated board. By means of five parallel folding lines, the sheet is divided into six parallel bands which are intended to form respectively a horizontal top wall provided along its edge with recesses each having the general shape of a portion of circumference extending over slightly more than 180° so as to engage in the grooves which are formed in the necks of the bottles and which are inserted in said recesses. Each recess is preferably provided with a flared entrance, a rear vertical wall, a base, a front vertical wall of lower height than the rear vertical wall, a sloping wall provided opposite to the recesses with sheared openings designed to accommodate the bottle bodies, and a flange which is intended to be folded flatwise against the internal face of the rear vertical wall.

This invention relates to a display carton for bottles, flasks, pots or like vessels which are each provided with a grooved neck.

The aim of the invention is to provide a display carton for objects of the above-mentioned type hereinafter referred-to as bottles, the design function of said carton being to afford protection against shocks during handling operations and also to afford visibility over a large area of each bottle, especially for the purpose of displaying any inscriptions which may be printed thereon.

The display carton in accordance with the invention is characterized in that it consists of a sheet of paperboard or like material and preferably corrugated board of rectangular shape which is divided by five folding lines parallel to two opposite edges of said sheet into six parallel bands which are intended to form by folding along the aforesaid lines respectively a horizontal top wall provided along its edge with recesses each having the general shape of a portion of circumference extending over slightly more than 180° so as to engage in the grooves which are formed in the necks of the bottles and which are inserted in said recesses, each recess being preferably provided with a flared entrance, a rear vertical wall, a base, a front vertical wall of lower height than the rear vertical wall, a sloping wall provided opposite to the aforesaid recesses with sheared openings designed to accommodate the bottle bodies, and a flange which is intended to be folded flatwise against the internal face of said rear vertical wall.

By virtue of this particular structure, it is possible not only to provide suitable protection of bottles, flasks or like articles which are nevertheless permitted to remain visible but also to remove and replace one or a number of such articles at will without thereby damaging the display holder.

In an advantageous form of execution, the material which is derived from the sheared openings is maintained attached to the flange and in the same plane as said flange.

A better understanding of the invention will be gained from a perusal of the following description and from

2

consideration of the accompanying drawings which show by way of non-limitative example one form of execution of a display carton in accordance with the invention.

In these drawings:

FIG. 1 shows a sheet which is intended for the fabrication of a display carton according to the invention;

FIG. 2 is a partial front view of the display carton after assembly and fitted with bottles;

FIG. 3 is a vertical sectional view taken along the line III—III of FIG. 2.

The display carton which is illustrated in the drawings is formed by folding a sheet of the type shown in FIG. 1, namely a sheet of paperboard or like material, preferably corrugated board, of rectangular shape and generally designated by the reference 1. Said sheet is divided by five folding lines 2, 3, 4, 5, 6 which are parallel to two opposite sides of said sheet into six parallel bands 11, 12, 13, 14, 15, 16 respectively. The band 11 is intended to form a top horizontal wall of the display carton, and is provided along its outer edge with recesses 18, of which there are five in the example shown, for the purpose of holding five pots or bottles; said recesses each have the general shape of a portion of circumference which extends over slightly more than 180° in such a manner as to form locking noses such as the nose 19. As shown at 21, the entrance of each recess has a flared portion in order to facilitate the insertion of bottles.

The band 15 is provided with five corresponding perforations or sheared openings 23 of suitable dimensions for ensuring that the body of each bottle is gripped within each sheared opening. In the example illustrated, the sheared shape 24 which is derived from said openings is maintained attached to the flange formed by the last band 16 of the sheet. In other words, the portion which is indicated at A and B, for example, in the case of one of said sheared openings is not sheared but forms a folding line.

The widths of the different bands of the sheet, the dimensions of the recesses 18 and the dimensions of the sheared openings 23 are so determined that bottles such as the bottle 26 (as shown in FIGS. 2 and 3) should be suitably held in the display carton by folding the sheet 1 along folding lines 2 to 6 in the manner shown in FIGS. 2 and 3. In particular, the edges of the recesses 21 are adapted to grip the neck 27 of each corresponding bottle whilst the wall which is formed by the band 15 takes up a sloping position which leaves the bottles 26 exposed at the front to a very appreciable extent so that said bottles can readily be seen in the positions which they occupy in the holder and any inscriptions on said bottles can in particular be read without difficulty. The display holder also leaves the caps 28 of the bottles completely free, with the result that any inscriptions printed on the cap can also be easily read.

From FIGS. 2 and 3, it is therefore apparent that the band 11 forms a horizontal top wall of the display carton, the band 12 forms a rear vertical wall, the band 13 forms a base, the band 14 forms a front vertical wall of small height, the band 15 forms an oblique wall which slopes upwards towards the rear and the band 16 forms a flange which is applied flatwise against the inner face of the rear vertical wall 12 between the bottle 26 and said wall. Moreover, the material 24 of the sheared openings formed in the oblique wall is located in the same plane as the flange 16 and applied flatwise against the rear vertical wall 12.

Each bottle is thus effectively maintained on the one hand laterally by means of the edges of the openings 23 and, on the other hand at the bottom both at the front and at the rear by the front vertical wall 14 and rear vertical wall 12 respectively as well as at the top by means of locking element formed by the narrowed portions 19

of the recesses 18 of the top wall 11. By virtue of the elasticity of the material of which the sheet is made, it is possible if so desired to withdraw either one or a number of bottles and to replace them in position without thereby damaging the display carton.

In an alternative arrangement, the material 24 of the sheared openings 23 which are formed in the oblique wall 15 could be removed completely.

As will readily be understood, the invention is not limited to the form of execution which has been described and illustrated and that modifications could be made therein without consequently departing from the scope or the spirit of the invention.

I claim:

1. A display carton for bottles, flasks, pots or the like which are each provided with a grooved neck, characterized in that said carton is constituted by a sheet of paperboard or like material and preferably of corrugated board of rectangular shape which is divided by five folding lines parallel to two opposite edges of said sheet into six parallel bands which are intended to form by folding along the aforesaid lines respectively a horizontal top wall provided along its edge with recesses each having the general shape of a portion of circumference extending

over slightly more than 180° so as to engage in the grooves which are formed in the necks of the bottles and which are inserted in said recesses, each recess being preferably provided with a flared entrance, a rear vertical wall, a base, a front vertical wall of lower height than the rear vertical wall, a sloping wall provided opposite to the aforesaid recesses with sheared openings designed to accommodate the bottle bodies, and a flange which is intended to be folded flatwise against the internal face of said rear vertical wall.

2. A display carton in accordance with claim 1, wherein the material derived from the sheared openings is maintained attached to the flange and in the same plane as said flange.
